COMBINATION COVER AND DISPENSING FAUCET

Thomas Carvel, Hartsdale, N. Y.

Application August 25, 1951, Serial No. 16,441

Term of patent 14 years

(Cl. D52—2)

To all whom it may concern:

Be it known that I, Thomas Carvel, a citizen of the United States, residing at Hartsdale, in the county of Westchester and State of New York, have invented a new, original, and ornamental Design for a Combination Cover and Dispensing Faucet, of which the following is a specification, reference being had to the accompanying drawing, forming part thereof.

Fig. 1 is a front elevation of a combination cover and dispensing faucet, showing my new design.

Fig. 2 is a rear view thereof;

Fig. 3 is a side view thereof;

Fig. 4 is a bottom view thereof; and

Fig. 5 is a top view thereof.

I claim:

The ornamental design for a combination cover and dispensing faucet, as shown.

THOMAS CARVEL.
